FIG. 2

UNITED STATES PATENT OFFICE

2,366,200

SHAPER

Howard C. Langhorst, Dayton, Ohio

Application August 3, 1943, Serial No. 497,224

4 Claims. (Cl. 90—13.2)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to improvements in shapers for duplicating patterned surfaces, particularly warped, irregular and non-planar surfaces such as propeller blades.

An object of the invention is to improve machines of the character by providing a universally adjustable pattern follower adjustably controlled automatically by the plane of the pattern transversely of the path of the follower to constantly bring the contacting surface of the follower into substantially parallel relationship with said transverse plane and further by providing a cutter remotely controlled by the follower to travel in angular unison therewith over the surface being developed in conformity with the pattern.

Another object of the invention is to provide an arrangement whereby a single cutter head is required for all shapes and contours to be developed.

Another object of the invention is to provide a shaper in which no balancing arrangement is necessary, such as in conventional types of shapers, for causing the cutter to follow in uniplane with and trailing of the pattern follower.

With the foregoing and other readily apparent objects and aims in view, my invention resides in the combination of parts and in the details of construction hereinafter set forth in the following specification and appended claims, certain embodiments thereof having the characteristics of my invention and by which the same may be practiced being illustrated in the accompanying drawings in which:

Fig. 1 is a plan view;

Fig. 2, a cross sectional view taken at line 2—2 of Fig. 1;

Fig. 3, an end elevational view of the universally mounted pattern follower angularly and pivotally disposed to illustrate a principle of operation; and

Fig. 4, a side elevational view taken at line 4—4 of Fig. 3.

The assembly illustrated for the purpose of explaining an embodiment of my invention includes a pair of elevated, horizontally disposed feed screws 10 and 11 rotatably mounted in spaced parallel relationship upon rectangularly disposed standards 12, 13, 14 and 15 fixed upon a base 16. The feed screws 10 and 11 are provided with means for rotating the same in uni-

son and are threaded to receive and drive a pair of traveling nuts 17 and 18. The upper portion of each of the respective traveling nuts 17 and 18 is slotted from the top downward to provide yokes or saddle-like guideways 19 and 20 transversely of the direction of the travel of the nuts upon the feed screws.

Spring seats 21 and 22 are positioned within the saddle-like guideways 19 and 20 and a non-rotatable slide bar 23 is suspended horizontally thereacross. Means are provided for causing the slide bar to be reciprocatingly moved, to-and-fro, longitudinally of itself through the slots 19 and 20. Such means may suitably consist of a feed screw 15 24 rotatably coupled to an end of the slide bar 23 operable through a traveling nut 25 resiliently mounted slidably on a fixed track 26.

The slide bar 23 is provided with three bearings 27, 28 and 29, upon which equal length arms 20 30, 31, and 32 are pendulously mounted. The arms are free to swing, or be moved, through equal predetermined arcs limited by stops 34 and 35. Upon the depending ends of the arms 30, 31 and 32 wheel-yokes 36, 37 and 38 are universally mounted by suitable means such as a conventionally known ball and socket arrangement as illustrated, particularly in Fig. 3. The wheel-yokes carry axles 39, 40 and 41 which extend through the legs of the yokes and outwardly 25 beyond the plane of the outer surfaces thereof for purposes described immediately hereinafter.

Identical pattern follower-wheels 42 and 43 are mounted upon the axles of the universally mounted yokes 36 and 38 of the first and third arms 35 30 and 32 and upon axle 40 of yoke 37 of the middle arm 31 is mounted a cutter 44 having a diameter equal to that of the pattern wheels 42 and 43. The cutter may be rotatably driven by any suitable means, one of which may be a motor 45 mounted upon the cutter yoke 37 or axle 40.

In order to insure that the cutter travels an identical path and in uniplanar motion with the paths and the motions of the pattern follower 45 wheels 42 and 43, as the slide bar 23 is caused to reciprocate, identical rigid cradle-like frames 46 and 47 are swiveled to the opposite extensions 48—49, 50—51 and 52—53 of axles 39, 40 and 41 of the pattern follower wheels and cutter. By swiveling the rigid frames to the axles in some suitable manner, such as shown in Figs. 3 and 4 at references 54 and 55, the wheels 42 and 43 and cutter head 44 are allowed to pivot in unison about vertical axes, while the universal connections between arms 30, 31 and 32 and the

yokes 36, 37 and 38 allow the wheels and cutter to tilt or pivot in unison about horizontal axes. As the surface of the patterns causes the wheels to pivot about vertical axes, the rectangles formed by the frames 46 and 47 and axles 39, 40 and 41, in plan as shown in Fig. 1, take the form of rhomboids. By this arrangement the contacting surfaces of the pattern follower wheels may be automatically maintained in parallel with the surfaces of the patterns being traversed and the cutter is controlled by the frames 46 and 47 to follow in unison.

Upon the base 16 are mounted a pair of patterns 56 and 57 of identical shape, size and contour with that of the duplicates desired to be produced. These patterns are positioned with their center lines in parallel and spaced a distance equal to that of the space between the axles 39 and 40 of the pattern follower wheels 42 and 43. The patterns are maintained in spaced parallel relationship by any suitable means, such as bolts 58, whereby reverse or other patterns may be substituted. The piece of stock 59 from which the duplicate is to be fashioned, is disposed centrally of the patterns, parallel therewith and secured in some suitable manner as by clamps 60.

By the structure described, the pattern wheels will tilt and pivot in unison as shown in Fig. 4, so as at all times to maintain the surfaces thereof in parallelism with each successive fractional portion of the patterns in the paths of the wheels as they are drawn to-and-fro by reciprocation of the slide bar and by reason of the cradle connection of the cutter head with the wheels, the cutter head angle is maintained in unison with that of the wheels for the production of a duplicate surface.

In operation the slide bar is drawn longitudinally of itself until the pattern follower wheels traverse the patterns, the feed screws are adjusted for a return swath, and the slide bar is then pushed or drawn in the reverse direction. In reversing the direction of travel, the arms 30, 31 and 32 move from contact with one of the stops 34 or 35 into contact with the other and there held rigid by the downward load of the slide bar. This process is continued until, by successive swaths, the patterns have been traversed, whereupon the partially patterned stock 59 is overturned, reverse patterns substituted, and the operation repeated.

By the permissible swing of the arms 30, 31 and 32, the wheels 42 and 43 and the cutter 44 are trailingly drawn over the patterns and the stock at a constant angle in order that they may properly seat and guide themselves over the course in uniformity. During the rise and fall of the wheels as they approach, and descend from, the summits of the patterns, the trailing angle of the arms 30, 31 and 32 is allowed to remain constant by the floating arrangement of the slide bar in the saddles or yokes 19 and 20 of the traveling nuts 17 and 18. By the use of two or more identical patterns and suitable pattern followers secured to traverse the patterns in unison, the cutter, suspended therebetween, is forced to travel on an identical plane, an identical angle, and simultaneously with the pattern followers.

Having described my invention and illustrated an embodiment whereby the same may be practiced, what I claim is:

1. In combination with a suspended slide bar of a shaper and means for reciprocally moving the bar longitudinally of itself as well as transversely thereof in a broadside manner, the im-

provement comprising a pair of spaced pattern followers connected to said bar universally tiltable about horizontal axes and pivotal about vertical axes, a cutter head suspended intermediate of said followers and on a plane therewith, and frame means for causing said followers and cutter head to move in unison throughout all tilts about horizontal axes and rotatory movements about vertical axes as the followers are caused to traverse the contours of patterns by the reciprocation of the slide bar.

2. A surface duplicating device comprising the combination of a base having means for securing a pair of like patterns with similar predetermined lines thereof in spaced parallel relation and for securing a blank piece of stock intermediately thereof, a pair of feed screws horizontally disposed above said base upon standards and in spaced substantially parallel relationship with one another, a traveling yoke mounted on each of said feed screws, means for driving said feed screws to move said yokes in unison, a slide bar slidable through and suspended in said yokes, means for reciprocating said bar longitudinally of itself, like pattern followers carried by said bar and adapted to be moved contactingly over said patterns in unison, means permitting said followers to automatically maintain their transverse pattern contacting surfaces in parallel with the successively traversed portions of said patterns on a plane transverse of the path of the pattern followers, a cutter operable upon said piece of stock, and means for causing said cutter to move through the same planes with said followers and with its contacting surface in angular unison with the follower contacting surfaces.

3. In combination with a suspended slide bar of a shaper and means for reciprocally moving the bar longitudinally of itself, the improvement comprising a pattern follower connected to said bar universally tilttable about horizontal axes and pivotal about vertical axes independently of said bar, a cutter head suspended from said bar to a plane with said follower, means for causing said follower to maintain its pattern contacting surface parallel to the plane of the successively contacted pattern surfaces, means for causing said cutter head to move in unison with said follower throughout all of its planes of travel over said pattern and in unison therewith throughout all tilts about horizontal axes and rotatory movements about vertical axes as the follower is caused to traverse or follow the contours of a pattern by the reciprocation of the slide bar.

4. A surface duplicating device comprising the combination of a base having means for removably securing a pattern and a blank piece of stock, a slide bar, means for reciprocating said bar longitudinally of itself, means for maintaining said bar in substantially parallel relationship with said base, means for moving said horizontally maintained bar to and from planes parallel therewith, a pattern follower carried by said bar and adapted to be moved contactingly over said pattern, means automatically maintaining the surface of the follower and the contacted portion of the pattern in parallel in a direction transverse of the path of the follower, a cutter operable upon said piece of stock, and means for causing said cutter to move through the same plane with said follower and with its contacting surface in angular unison with the pattern contacting surface of the follower.

HOWARD C. LANGHORST.
